MAGNETIC POWDER DISPENSER

Byron H. Acomb, Watchung, Robert G. Pennstrom, Livingston, and Donald W. Carkhuff, Newark, N. J., assignors to Union Carbide Corporation, a corporation of New York

Application August 31, 1956, Serial No. 607,421

2 Claims. (Cl. 302—51)

This invention relates to magnetic powder dispensers, and has for its main object to facilitate the operation and maintenance of dispensers of this character.

The dispenser comprises a hopper, a distributor chamber receiving from said hopper, magnetic means rotatably mounted in said chamber, and regulator tube means from said hopper to said distributor means. A particular object of the present invention is to provide means actuated by turning the hopper to adjust the regulator means.

Another object is to provide a removable bearing housing in the distributor casing, journaling a drive shaft for said magnetic distributor means and containing powder seals therefor, all removable with said bearing housing as a package unit.

In the drawings:

The single figure is a vertical section through a magnetic powder dispenser according to the preferred embodiment of the present invention.

The dispenser shown comprises a hopper 10 bolted to a threaded sleeve 12 screwed into a vertical bore in distributor casing 14. The sleeve 12 has a flared upper portion in its central bore, forming a conical throat 15 to funnel the powder to the discharge nozzle or regulator tube 16 screwed into the bottom of the central bore in the threaded sleeve 12. A calibrated ring 17 mounted on the sleeve 12 cooperates with a pointer 18 fixed on the casing 14. A pressure equalizing tube 19 extends through the sleeve 12 to the space above the powder in the hopper 10, to equalize the pressure above the powder with the pressure in the distributor chamber.

The distributor casing 14 has a transverse bore in which is mounted a bearing housing 20. The housing 20 contains ball bearings 22 and 24, journaling a drive shaft 25 for a magnet drum 26 secured on the inner end of the shaft below the nozzle 16. The bearings 22 and 24 position the drive shaft 25 and permit it to rotate freely.

A virtually frictionless pressure seal around the shaft is provided by the O-ring 28 and the Teflon bushing 30. The combination of the ball bearing positioner and this frictionless seal permits the use of a low-rated motor for the shaft drive. Leakage of powder around the shaft is prevented by oil saturated felt wipers 32. The cartridge type assembly consisting of the shaft 25, bear-

2

ings 22 and 24, bearing housing 20, seals 28, 30 and 32, and magent 26 permits disassembly of these parts from the casing 14 as one unit.

The powder from the hopper 10 is discharged through the throat 15 in the sleeve 12 and the nozzle 16 into the distributing chamber in the casing 14, to adhere to and build up as a layer on the rotating magnetic drum 26. As the drum rotates to a point approximately one-half a turn, a scraper 33 removes the material from the drum and the material passes to an injection chamber 34 in the base of the casing 14 where it is mixed with and suspended in a stream of carrier gas.

The flow rate of the powder can be varied between one pound per hour to more than twenty-five pounds per hour at thirty revolutions per minute of the drive shaft 25 by turning the hopper 10 and thereby turning the threaded sleeve 12, which controls the distance of the nozzle 16 from the magnet 26. This range will vary with other speeds of the drive shaft. The calibrations on the ring 17 permit resetting this distance to reproduce a desired flow rate.

What is claimed is:

1. In apparatus for suspending in a stream of carrier gas a powdered composite material including a closed material hopper communicating at the base with discharge port means, a closed material distributing chamber in communication with said discharge port means and having at its base an outlet passage, and suspending gas conduit means in communication with said outlet passage for suspending said composite material in a stream of carrier gas conducted therethrough, conveyor means rotatably mounted in said distributing chamber, and regulator tube means positioned above said conveyor means for discharging a controlled quantity of said composite material on the surface of said conveyor means to collect thereon a layer of said composite material, the improvement which comprises means actuated by turning said hopper for adjusting said regulator tube means, and a removable bearing housing in said distributor chamber journaling a drive shaft for said conveyor means and containing powder sealing means therefor, all removable with said bearing housing as a package unit.
2. Apparatus for suspending in a stream of carrier gas a powdered composite material as claimed in claim 1, in which said composite material has a ferromagnetic component, and said conveyor means rotatably mounted in said distributing chamber is a magnetic conveyor means.
